UNITED STATES PATENT OFFICE

JOSEPH E. FAWELL, OF PITTSBURGH, PENNSYLVANIA, ASSIGNOR TO INDUSTRIAL METHODS COMPANY, OF PITTSBURGH, PENNSYLVANIA, A CORPORATION OF DELAWARE

ROLLING MILL

Application filed October 4, 1928. Serial No. 310,219.

The invention relates to rolling mills of the type shown in Patents No. 1,360,959 and No. 1,655,063 to Arnold Kriwan, which comprises small diameter working rolls backed by sleeves rotatably mounted on fixed mandrels borne by the roll housing.

The object is to improve the construction of this type of rolling mills to the end that the working rolls and their backing sleeves and mandrels may be more readily placed in and removed from the housing; that the backing sleeves may have increased strength to resist deflection, and may be more accurately placed and held in roll-supporting positions; and that there may be greater pressure between the working rolls and their supporting sleeves to increase the rotating force applied by the former to the latter.

The invention is illustrated in the accompanying drawings, of which Fig. 1 is an end view of a rolling mill, certain portions being shown in section; Fig. 2 a combined face and vertical central sectional view of the mill; and Fig. 3 a plan view of the mill.

In the mill provided according to this invention upper and lower working rolls 1 and 2 of relatively small diameters and of cylindrical form for rolling sheet metal are suitably mounted in a housing 3, the ends of the rolls being shaped to receive wabblers for driving them. The roll necks are shown as being mounted in plain bearings, the necks of upper roll 1 are mounted in bearing cages 4, and those of lower roll 2 in bearing cages 5. For positioning the rolls with their axes parallel to each other, and for so maintaining them, the housing is provided with adjusting bolts 6 (Fig. 1), the inner ends of which abut against blocks 7 which bear upon the ends of cages 4 and 5. These bolts are provided at their outer ends with angular heads for turning them, and they may be locked in adjusted positions by nuts 8. The rolls are held against endwise movements by suitable keeper plates 9 which engage the outer faces of cages 4 and 5 and are adjustably attached to the roll housing by bolts 10.

Arranged above and below the working rolls there are fixed mandrels 15 and 16, on which there are rotatably mounted sleeves 17

and 18, respectively, for supporting the working rolls against deflection. Each end of each sleeve is provided with an annular recess 19 for receiving a set of roller bearings. Since the construction of mandrel 15, sleeve 55 17 and the roller bearings between them may be, and preferably is the same as that of mandrel 16, sleeve 18 and the bearings between them, further detail description will be confined to the upper mandrel and sleeve. 60

Each roller bearing comprises a bearing ring 20 mounted on mandrel 15 adjacent to its end, bearing rings 21 mounted on the walls of the recesses 19 of the sleeve, and conical roller bearings 22 arranged between 65 these rings. At the right side of the mill as viewed in Fig. 2, a narrow backing ring 23 is arranged between bearing ring 20 and a block 24 supporting the right end of the mandrel which is threaded to receive a nut 70 25 abutting against the outer face of block 24. At the left side of the mill a longer backing ring 23a is arranged between bearing ring 20 and a nut 26 screwed upon the mandrel, ring 23a extending through a block 75 24a. By tightening nut 26 upon the mandrel, nut 25 is brought to bear against block 24, and backing ring 23a is forced against bearing ring 20 at the left of the mill to position rings 20 between the sleeve and mandrel, and hence the sleeve upon the mandrel. Nuts 25 and 26 are locked, and in consequence thereof the mandrel is held in fixed position, by dogs 27 attached to blocks 24 and 24a and 80 engaging one of a plurality of notches 85 formed on the periphery of the nuts. Blocks 24 and 24a are provided with flanges 28 (Fig. 1) which bear against the outer faces of housing 3. Spanning the gap between the end of sleeve 17 and the peripheries of backing rings 23 and 23a, there are cover plates 30 bolted to the end of the sleeve and provided on their inner faces with flanges which bear against the outermost of the pairs of rings 21. 90

The roller bearings are run in a suitable 95 lubricant such as oil or grease placed in recesses 19 and retained therein by suitable packings arranged between cover plates 30 and backing rings 23 and 23a. Between its end recesses 19, sleeve 17 is substantially in 100

contact with mandrel 15, there being but a small clearance between the two. By such construction the sleeve has maximum wall thickness and consequent increased strength to resist deflection by the pressure imposed upon it by working roll 1.

Bearing upon the tops of blocks 24 and 24a, there are breaker blocks backed by the lower ends of adjusting screws 35 against which mandrel 15 and sleeve 17 are balanced in their upward position by spring mechanism; although as far as concerns some features of the invention any suitable balancing means may be used. As here illustrated, each end of mandrel 15 is engaged by an eye 26 pivotally attached by a pin 37 to the lower end of a suspension bar 38, the upper end of which is attached to the lower end of a rod 39 extending upwardly through a shelf 40 connected to the housing, and also upwardly through a floating bar 41, the upper end of each rod 39 being provided with an adjusting nut 42. At the sides of rod 39 there are rods 43 which also extend through shelf 40 and bar 41. Surrounding rods 39 and 43 there are springs 34 which bear at their upper and lower ends against bar 41 and shelf 40, the tension of which springs may be varied by adjusting the nuts 42 on rods 39. At their lower ends rods 43 are provided with nuts 45 for a purpose presently to be explained.

While various means may be provided for positioning the adjusting screws, each is here shown as having a worm wheel 50 keyed for longitudinal movement upon and for rotation with the upper end of the screw. Through suitable reduction gears 51, each of these worm wheels is adapted to be independently rotated by a reversible motor 52, and for effecting simultaneous adjustments of the screws a suitable clutch 53 is arranged between the driven shafts of the two motors and adapted to be controlled by a lever 54.

For urging the working rolls into firm bearing contact with the sleeves to properly effect rotation of the latter by the former, cages 5 are provided with rods 60 extending upwardly through them, and surrounding each of these rods there is a spring 61 which bears against the bottom of the cage and against a shoulder 62 formed on the rod. At their lower ends, rods 60 are provided with nuts 65 for restraining the action of springs 61 while the working rolls are being placed in and removed from the housing. The cages for the upper working rolls are provided with rods 63, screw threaded at their lower ends for vertical adjustments in the cages and provided at their upper ends with nuts 64 for holding them in their adjusted positions. The lower ends of rods 63 abut against the upper ends of rods 60, and by adjusting the positions of rods 63 the tension in springs 61 may be altered to apply a variable pressure

between the rolls with resulting variations in the pressures of the rolls upon their respective mandrels.

As shown in Fig. 1, the roll housing is provided with windows sufficiently wide to permit sleeves 17 and 18 and their supporting mandrels 15 and 16, together with the blocks 24 and 24a which support the mandrels, to pass through the windows when these parts are assembled as units. When it is desired to remove the upper backing unit from the housing, adjusting screws 35 are moved upwardly, and nuts 45 on rods 43 are adjusted to position the unit below the lower ends of the adjusting screws, with sleeve 17 above the upper working roll. Nuts 65 on rods 60 arranged in lower working roll cages 5 are tightened on these rods so that springs 61 will cease to act upon rods 60 to force the upper working roll against sleeve 17. With the several parts thus adjusted, eyes 36, nuts 25 and 26 and blocks 24 and 24a may be removed, suspension rods 38 disconnected from eyes 36, and the unit then removed longitudinally from the housing.

With the upper backing sleeve unit in its upper position and nuts 65 so adjusted on rods 60 that the rolls are not separated by the action of springs 61, the pair of working rolls and their bearing cages may then be removed simultaneously, after which the lower backing unit may be removed. If desired, a truck or buggy may be run through the housing window or windows for carrying the backing units to and from the housing.

The mill here provided is primarily for rolling sheet metal without substantial variations in its thickness from edge to edge of the pass. The rolling is effected by small diameter working rolls having well known advantages, and the rolls are backed by very rigid sleeves which are mounted upon strong mandrels. Accordingly, the working rolls are held against deflection, and because the sleeves rotate readily upon roller bearings there is no thermal expansion of the sleeves due to frictionally generated heat. The working rolls and their backing sleeves may be readily adjusted to place their several axes in proper positions, and each may be conveniently removed from the roll housing without disassembling its mounting.

According to the provisions of the patent statutes, I have explained the principle and operation of my invention, and have illustrated and described what I now consider to represent its best embodiment. However, I desire to have it understood that, within the scope of the appended claims, the invention may be practiced otherwise than as specifically illustrated and described.

I claim as my invention:

1. A rolling mill comprising a housing, upper and lower working rolls mounted in the housing, upper and lower backing sleeves

for the rolls, upper and lower fixed mandrels extending through said sleeves, roller bearings between said mandrels and sleeves for rotatably supporting the latter, yielding means arranged on the outer faces of the housing engaging the ends of said upper mandrel and suspending it and its surrounding sleeve in variable upper positions, and yielding means acting between said working rolls for urging them into firm bearing contact with their respective supporting sleeves.

2. A rolling mill comprising a housing, upper and lower working rolls mounted in the housing, upper and lower backing sleeves for the rolls, upper and lower fixed mandrels extending through said sleeves, roller bearings between said mandrels and sleeves for rotatably supporting the latter, suspension rods arranged on the outer faces of the housing engaging the ends of said upper mandrel, springs acting between said rods and the housing for holding the upper mandrel upwardly, and yielding means acting between said working rolls for urging them into firm bearing contact with their respective supporting sleeves.

3. A rolling mill comprising a housing, upper and lower working rolls mounted in the housing, upper and lower backing sleeves for the rolls, upper and lower fixed mandrels extending through said sleeves, roller bearings between said mandrels and sleeves for rotatably supporting the latter, eyes surrounding the ends of said upper mandrel, suspension rods removably attached at their lower ends to said eyes, springs acting between the upper ends of said rods and the housing for holding the upper mandrel upwardly, and yielding means acting between said working rolls for urging them into firm bearing contact with their respective supporting sleeves.

4. A rolling mill comprising a housing, upper and lower working rolls mounted in the housing, upper and lower backing sleeves for the rolls, upper and lower fixed mandrels extending through said sleeves, roller bearings between said mandrels and sleeves for rotatably supporting the latter, yielding means arranged on the outer faces of the housing engaging the ends of said upper mandrel and suspending it and its surrounding sleeve in their upper position, and springs acting between the ends of said working rolls for urging them away from each other and into firm bearing contact with their respective supporting sleeves.

5. A rolling mill comprising a housing, upper and lower working rolls mounted at their ends in bearing cages arranged in the housing, upper and lower backing sleeves for the rolls, upper and lower fixed mandrels extending through said sleeves, roller bearings between said mandrels and sleeves for rotatably supporting the latter, yielding

means engaging the outer ends of said upper mandrel for holding it and its surrounding sleeve upwardly, longitudinal adjustable rods extending through and attached to the upper roll bearing cages, and spring impelled rods arranged in and extending through said lower roll bearing cages and acting upon the lower ends of said adjustable rods to urge the roll cages away from each other and their respective rolls into firm bearing contact with their supporting sleeves.

In testimony whereof, I sign my name.
JOSEPH E. FAWELI.
